UNITED STATES PATENT OFFICE.

LOUIS MYERS, OF HARTFORD, CONNECTICUT, ASSIGNOR TO UNDERWOOD TYPEWRITER COMPANY, OF NEW YORK, N. Y., A CORPORATION OF NEW JERSEY.

MARGIN PAPER-GUIDE FOR TYPE-WRITING MACHINES.

SPECIFICATION forming part of Letters Patent No. 738,927, dated September 15, 1903.

Application filed March 3, 1903. Serial No. 145,928. (No model.)

To all whom it may concern:

Be it known that I, LOUIS MYERS, a citizen of the United States, and a resident of Hartford, county of Hartford, and State of Connecticut, have invented certain new and useful Improvements in Margin Paper-Guides for Type-Writing Machines, of which the following is a specification.

My invention relates to paper-guides for type-writing machines, and particularly to those guides which are employed to press the marginal portion of the paper against the platen.

The object of my invention is to provide a simple construction which may be readily adjusted lengthwise of the platen to correspond to paper of various widths, which will take very little room, and which will not obstruct the operator's view of the type-written matter.

The invention will be fully described hereinafter and the features of novelty pointed out in the appended claims.

Reference is to be had to the accompanying drawings, which illustrate a typical example of my invention.

Figure 1 is a front elevation showing the platen portion of a type-writer provided with my improvement. Fig. 2 is a sectional elevation on line 2 2 of Fig. 1. Fig. 3 is a longitudinal section on line 3 3 of Fig. 4, and Fig. 4 is a cross-section on line 4 4 of Fig. 1.

A indicates a portion of the carriage-frame, in which the platen B is journaled. To this frame A is secured adjacent to each end of the platen, as at A', a bracket C, which at its upper end is formed with a stationary carrying-section D, extending above the platen and lengthwise of the same. While this carrying-section is shown integral with the bracket C, I desire it to be understood that the bracket and the carrying-section may be separate pieces. A tubular carrying-section is illustrated; but I do not restrict myself to such specific construction. With the carrying-section is slidably connected an extension E, which is thus adapted to move lengthwise of the platen or parallel with the axis thereof. Preferably means are provided for preventing the extension E from turning rela-

tively to the carrying-section D, as a pin D', fitting a longitudinal groove E² of the extension E. The section D and extension E are preferably telescopic, as shown, and I may add similar extensions F G to increase the scope of movement or adjustment. Each of these sections may be connected with the preceding one which carries it by a pin and groove, the pins being designated as E' and F' and the grooves as E² and G'. The last section or extension G, which I will term the "guide-section," (because it carries the guide directly,) may be solid, while the other sections are tubular and increase in diameter toward the carrying-section D; but this arrangement, while preferred, is not essential.

The guide proper comprises an elastic curved strip H, arranged to fit the periphery of the platen and secured to the guide-section G in any suitable manner, as through the medium of a short sleeve J, held in place by a set-screw K. A margin feed-roller L may be journaled on the guide-strip H, so as to project therefrom and engage the upper portion of the platen.

The groove and pin of the same section E F are preferably diametrically opposite each other, and as a consequence the pins D' E' F' of successive sections or members are alternately on opposite sides of the center or axis. The sections D E F G together form an extensible and in the particular structure shown a telescopic carrier for the guide proper, H. The number of these sections may be increased or reduced.

It will be understood that when the carrier is folded or contracted the guide proper, H, remains at the inner end of the carrier, or, in other words, whatever position the guide may be adjusted to no part of the carrier will project inwardly beyond the guide, so that under all circumstances the paper between the two guides will be fully exposed to view. The folding or extensible construction of the carrier is further of great advantage on account of its lightness and compactness, and, moreover, no part of the carrier will in any adjustment thereof project outwardly beyond the stationary section of the carrier.

Various modifications may be made with-

out departing from the nature of my invention.

What I claim as new, and desire to secure by Letters Patent, is—

- 5 1. In a type-writer or the like, the combination, with a carrier having a stationary tubular section, a sliding section arranged to extend lengthwise into said stationary section, and means for holding the sliding section against turning relatively to the stationary section, of a paper-guide projecting laterally from the free end of said sliding section.
- 10 2. In a type-writer or the like, the combination, with a carrier consisting of a plurality of nested sections increasing in thickness or diameter from section to section, one of said sections being stationary, of a paper-
- 15

guide connected with a movable section of the carrier.

- 20 3. In a type-writer or the like, a carrier consisting of a plurality of sections of substantially the same length, said sections being mounted to slide one upon the other in the same direction to form an extensible carrier, in combination with a paper-guide carried by 25 one of said sections.

In testimony whereof I have hereunto set my hand in the presence of two subscribing witnesses.

LOUIS MYERS.
